UNITED STATES PATENT OFFICE

163,283

NECKTIE HOLDER

Clarence Vain Hoffman, Whittier, Calif.

Application December 23, 1950, Serial No. 13,554

Term of patent 14 years

(Cl. D33—8)

To all whom it may concern:

Be it known that I, Clarence V. Hoffman, a citizen of the United States, residing in the city of Whittier, county of Los Angeles, State of California, have invented a new, original, and ornamental Design for a Neck Tie Holder, of which the following is a specification, reference being had to the accompanying drawing, forming a part thereof:

I claim:

The ornamental design for a neck tie holder as shown.

CLARENCE VAIN HOFFMAN.
